UNITED STATES PATENT OFFICE.

JOSEF DORNBUSCH, OF CREFELD, GERMANY.

DESIGN FOR LEATHER OR SIMILAR ARTICLE.

Application filed January 26, 1925. Serial No. 12,138. Term of patent 7 years.

To all whom it may concern:

Be it known that I, JOSEF DORNBUSCH, a citizen of Germany, residing in the city of Crefeld, in the Republic of Germany, have invented a new, original, and ornamental Design for Leather or Similar Article, of which the following is a specification, reference being had to the accompanying drawing, forming part thereof, which illustrates a surface view of a piece of leather or similar article embossed with my new design.

I claim:

The ornamental design for leather or similar article, as shown.

JOSEF DORNBUSCH.
